UNITED STATES PATENT OFFICE.

ABBOT AUGUSTUS LOW, OF HORSESHOE, NEW YORK, ASSIGNOR TO THE
AUTO STOPPER COMPANY, OF NEW YORK, N. Y.

BOTTLE MOUTH AND NECK.

SPECIFICATION forming part of Letters Patent No. 785,013, dated March 14, 1905.

Application filed June 28, 1904. Serial No. 214,501.

To all whom it may concern:

Be it known that I, ABBOT AUGUSTUS Low, a citizen of the United States, and a resident of Horseshoe, in the county of St. Lawrence and 5 State of New York, have invented certain new and useful Improvements in Bottle Mouths and Necks, of which the following is a specification.

My invention relates to vessel mouths and 10 necks; and it consists in certain elements in combination, fully set forth and claimed in the following specification.

In order that those skilled in the art to which my invention appertains may understand, construct, and use my invention, I will proceed 15 to describe it, referring to the accompanying drawings, forming part of this specification.

Figure 1 is a longitudinal elevation of a bottle and cap, showing my invention. The vessel 20 being of glass, the shape of the inner bore of the bottle is seen plainly delineated. Fig. 2 is a longitudinal central section of the same with a stopper resting in the mouth of the bottle beneath the retaining-cap after being entered 25 in the bottle-mouth and compressed into the shape shown. Fig. 3 is a top view of the bottle-mouth, showing my invention, the cap and stopper being removed.

A is the body of the bottle. 30 B is the bottle-neck. C is the cap, locked to the bottle by indents in the cap-flange entered through slots to take under a bead on the outer circumference of the bottle-neck in a well-known manner. 35 D is the inner bore of the bottle-neck at its top.

E is the inner bore of the bottle-neck at a distance below the part D.

F is a taper bore located between parts D and E and joins the two. 40

G is a stopper of compressible material entered in the bottle-neck in parts D, F, and E.

The stopper is of about the diameter of part D before being entered in the bottle-bore, and it is compressed in passing through part F to 45 the size of part E, thus when fully entered fitting closely all the parts D, F, and E and insuring a tightness throughout the whole of this part of the bottle-bore. The cap C holds the stopper firmly against the pressure from the 50 contents of the vessel.

The taper portion F serves to guide the stopper easily and smoothly from the larger bore D into the smaller bore E.

Having now fully described my invention 55 and the manner in which I have embodied it, what I claim as new and as my invention, and desire to secure by Letters Patent, is—

A vessel neck and mouth constructed substantially as specified and shown, with a circumferential bead on its exterior at its top, provided with vertical slots and, an internal bore of larger diameter above and smaller diameter below, joined the one to the other by a taper bore, substantially as specified. 60

Signed at New York, in the county of New York and State of New York, this 10th day of June, A. D. 1904.

ABBOT AUGUSTUS LOW
